ARTICLE OF FURNITURE

William J. Bargen, Waukegan, Ill.

Application April 27, 1937, Serial No. 139,315

8 Claims. (Cl. 155—134)

This invention relates to an article of furniture, such as a unit comprising a chair, desk, book box, arm rest and pedestal. The article of furniture is designed primarily for use in school and lecture rooms, but it is to be understood that it is to be employed in any connection for which it may be found applicable.

The invention has for its object to provide, in a manner as hereinafter set forth, a unit of the type referred to so constructed to provide for its being balanced to stay put on a floor whether anchored on or non-anchored to the latter and capable of being adjusted for use to afford maximum amount of comfort with respect to the disposition of the user's arms, feet and legs.

A further object of the invention is to provide, in a manner as hereinafter set forth, an article of furniture including a pedestal element, a chair element vertically adjustable relative to and supported by the pedestal element, a desk element bodily carried with the chair element, an arm rest element bodily carried by the chair and desk elements, and an open top receptacle or book box element bodily carried by the chair element, disposed at one side of the latter directly below and in laterally extended relation with respect to the arm rest of the chair element as well as extended rearwardly from the back.

A further object of the invention resides in the novel construction and arrangement of the book box element.

A further object of the invention resides in the setting up of the book box element with an inner wall, an outer wall arranged with its top and bottom edges below the top and bottom edges of the inner wall, a pair of side walls arranged between the said other walls and having their top and bottom edges inclining downwardly from the inner to the outer wall and a bottom inclining downwardly from the inner to the outer wall and having its ends spaced from the inner faces of the side walls.

A further object of the invention is to provide, in a manner as hereinafter set forth, a unit of the class referred to including a pedestal element having a base formed with a concave front, rear and side edges and with the front of the base of less width than the rear thereof.

A further object of the invention is to provide, in a manner as hereinafter set forth, a unit of the class referred to with a pedestal element having incurved front, rear and side bottom edges, front and rounded bottom corners, and curved protecting members constituting cushions for the base disposed outwardly and inwardly with re-

spect to the said bottom side edges and extending from the front to the rear bottom corners of the base.

A further object of the invention is to provide, in a manner as hereinafter set forth, a chair element including a seat member inclining downwardly from rear to front, a back member inclining rearwardly from its lower to its upper end and angle-shaped coupling members common to, overlapping and adapted to be secured to the said other elements for anchoring them together in angular relation.

Further objects of the invention are to provide, in a manner as hereinafter set forth, a unit of the type referred to which is comparatively simple in its construction and arrangement strong, durable, compact, balanced, readily adjusted, thoroughly efficient in its use, expeditiously assembled, having an arm rest element and a book box element, the arm rest element having a clearance to facilitate storing and removing of matter from the book box element, including reinforced chair and desk elements, which are comparatively inexpensive to manufacture.

Embodying the above ends essentially and others which may hereinafter appear, the invention consists of the novel construction, combination and arrangement of parts as will be specifically referred to and as illustrated in the accompanying drawings wherein is shown an embodiment of the invention, but it is to be understood that changes, variations and modifications may be resorted to which fall within the scope of the invention as claimed.

In the drawings:

Figure 11 is a section on line 11—11, Figure 10, Figure 12 is a section on line 12—12, Figure 10, Figure 13 is a section on line 13—13, Figure 9, Figure 14 is an inverted sectional plan of a modified form of arm rest and desk elements, 5 Figure 15 is a fragmentary view in rear elevation of the chair element, Figure 16 is a section on line 16—16, Figure 15, Figure 17 is a fragmentary view in transverse 10 section of the seat, 10 Figure 18 is a section on line 18—18, Figure 7, Figure 19 is a fragmentary view in top plan illustrating the flush arrangement of the outer 15 wall of the open top box receptacle with the outer side edge of the arm rest, 15 Figure 20 is a fragmentary view in perspective of the adaptation therewith of a modified form of foot piece or shoe, Figure 21 is an inverted plan of the structure 20 shown in Figure 20, Figure 22 is a section on line 22—22, Figure 20, and Figure 23 is a section on line 23—23, Figure 22. 25

The unit includes a pedestal element 20, a chair element 21, a desk element 22, an arm rest element 23 and a book box element 24. The element 20 includes a vertically adjustable section, to be referred to, which is secured at its upper end 30 to element 21 whereby when said section is adjusted the element 21 will be carried therewith. The elements 22, 23 and 24 are secured to element 21 whereby when the latter is adjusted elements 22, 23 and 24 will be carried therewith. 35

The pedestal element 20 includes a lower or stationary section 25 and an upper vertically adjustable section 26. The section 25 includes a hollow frusto-pyramidal base 27 formed with concave sides 28, a concave front 28^a, a concave rear 28^b, concave side edges 29, a concave rear edge 30, a concave front edge 31, rounded lower front and rear bottom corners 32, 33 respectively and flat peripheral facets 34 at the points of emergence of the sides 28 with said front 28^a and rear 28^b. The bottom of the front of base 27 is of less width 40 than the bottom of the rear of the base. The section 25 includes a hollow standard 35 of polygonal cross section open at its upper and lower ends. The standard 35 at its lower end merges into the upper end of base 27 as well as communicates with the latter. The corners 36 of the standard 35 are inclined and flat and form continuations of the facets 34. The length of standard 35 is as desired. The section 26 includes a hollow post 37 for extension into the standard 35. The cross sectional contour of post 37 corresponds to that of standard 35. The upper end of post 37 merges into and centrally of a reinforced H-shaped head 38 (Figure 3) which is anchored to the element 21. The post 37 and standard 35 are provided with adjustable coacting means 39 (Figure 2) for detachably securing the post 37 in its adjusted position. The said means may be of any suitable construction, by way of example, as shown by Patent 1,591,651 or by my co-pending application, Serial No. 139,316, filed April 27, 1937. Preferably it will be similar to that as disclosed in the application aforesaid. Positioned against the bottom of each of the sides 28 of base 27 is 55 a flat foot piece or shoe 39^a which acts as a bearing and cushioning means for the base 27. Each foot piece includes a flat strip 40 of a length to extend from an outer front corner 32 to a rear corner 33. The ends of the strips 40 are rounded 60 and extend outwardly from the corners 32, 33. 70

75

The strips 40 are curved and conform in contour to that of the side edges 29. Each foot piece 39^a includes circular depending portions 41 on the ends of the lower face of a strip 40 (Figure 7). The portions 41 possess a cushioning characteristic for the base. The foot pieces 39^a act as spacers for the base 27 and protectors for the support on which the unit is positioned. Countersunk holdfast means 42 are positioned at and extend through the lower corners of base 27 for 10 securing the latter and the strips 40 together. The strips 40 are of like form and oppositely disposed. 15

Each strip includes a flat metallic core 43 of arcuate contour and of strap-like form provided with an opening 43^a centrally of each end thereof and spaced openings 43^b disposed on its lengthwise median and interiorly threaded upstanding bushings 43^c, each anchored at its lower end in an opening 43^a. Each strip includes a flat housing 44 which completely envelopes the upper and lower faces and side and end edges of the core 43. The housing 44 is constructed from resilient material preferably rubber and conforms in curvature to that of the core and parts 44^a of the material from the housing 44 extend through the openings 43^b. The housing 44 is moulded around core 43. The housing surrounds and has its upper face flush with the upper ends of the bushings 43^c. The lower face of housing 44 is formed with 20 openings 44^b which align with the openings 43^a. The holdfast means 42 threadedly engages with the bushings 43^c. The portions 41 of the foot pieces or shoes are also employed to create friction at the floor to offset the necessity in many 25 cases of fastening to the floor. In other words, the said portions 41 of the foot pieces or shoes not only cushion the base, but they also create an element of friction at the floor and when the portions 41 are compressed by the weight of 30 the article to an extent to be flush with the remaining part of the shoe between the said portions 41 on the shoe, the said part will also create an element of friction at the floor, thus the reason the foot pieces are built on an arc is to create 35 the maximum amount of friction. The foot pieces or shoes are used for protection of the flooring 40 itself against undue marking. 45

The chair element 21 includes a rectangular seat 46 and a rectangular back 47. The seat 46 eccentrically of its lower face has secured thereto the head 38 of pedestal element 20. The seat 46 inclines downwardly from front to rear and extends forwardly from the lower end of back 47. The latter inclines rearwardly from its lower 50 to its upper end. The rear end of seat 46 and lower end of back 47 are formed with oppositely disposed rabbets 47^a, 47^b respectively (Figure 16) whereby the lower end of back 47 will rest on the rear end of seat 46. Arranged against a portion of the length of the side edges of the seat and back and secured against spaced parallel portions of the length of the lower face of seat 46 and spaced parallel portions of the rear face of back 47 is a pair of oppositely disposed upstanding combined coupling and reinforcing members 48, 49 of angle contour and like form. Each of the members 48, 49 and includes an intermediate portion 50 substantially of triangular contour and section formed with a curved upper edge, a straight outer side and a straight base. The portion 50 at its outer side is formed with an inwardly extending flange 51 and at its base with an inwardly extending flange 52 disposed at right angles to the flange 51. Each 55 60 65 70 75 80 85 90 95 98

of the members 48, 49 includes an upstanding upper stretch 53 formed of a pair of flanges 54, 55 disposed at right angles to each other. Each of the members 48, 49 includes a horizontally disposed lower stretch 56 formed of a pair of flanges 57, 58 disposed at right angles to each other. With respect to the member 48 or 49 the portion 50 thereof is arranged between and merges into the flanges 54, 57. The flanges 51, 52 of portion 50 merge into each other and into the flanges 55, 58. The portion 50 at the point of mergence of the flanges 51, 52 is rounded, as at 59, to prevent the forming of sharp corners whereby the possibility of damaging the outer garment of the wearer is reduced to a minimum. The portions 50 of the members 48, 49 are arranged against and extend upwardly and horizontally from the points of joinder of the back and seat. The portions 50 of the members 48, 49 are disposed against the side edges of the seat and back adjacent said point of joinder. The flanges 54 of the members 48, 49 are positioned against a portion of the length of the rear face of the back 47. The flanges 57 of the members 48, 49 are positioned against a portion of the length of the side edges of the seats 46. The flange 51, 55 of the members 48, 49 are positioned against the side edges of the back 47 and secured thereto by the holdfast means 59 (Figure 15). The flanges 52, 58 are positioned against edge portions of the lower face of the seat 46. The flanges 52, 58 are anchored to the seat 46 by spaced holdfast means 60 (Figure 3).

The desk element 22 and arm rest element 23 are integral with each other and formed from a one-piece body 61 of suitable material, preferably wood. The body 61 consists of a rectangular part 62 and an extension 63 (Figures 1 and 9) which merges into the left end terminal portion (Figure 1) of the rear edge of part 62. The part 62 of body 61 constitutes the desk element 22 and the extension 63 the arm rest element 23. The width of part 62 is greater than that of back 47. The part 62 when looking towards its front will have its right side edge disposed substantially flush with the right side edges of the seat and back and its left side edge disposed in laterally extended relation with respect to the left side edges of the seat and back. The part 62 may have its upper face in proximity and parallel to its front or forward edge 64 provided with a groove to receive writing instruments. The lower face of part 62 in proximity to its edge 64, has secured thereagainst a reinforcing angle iron 65 which extends into said part 62 (Figures 9 and 13). The lower face of part 62 in proximity to its rear edge 66 has secured thereagainst the horizontal flange 67 of an angle bar 68 constituting a reinforcement for part 62 as well as a means for connecting to part 62 a combined coupling and supporting structure 69 (Figures 1 and 2), to be referred to, for desk element 22. The bar 68 includes an apertured vertical flange 70 which depends from the front of flange 67.

The extension 63 which constitutes the arm rest element 23 has its inner side edge 71 cut out as at 72 to provide a clearance for a purpose to be referred to. The rear end edge 73 of extension 63 is rounded. The extension 63 is of the desired width and length.

The structure 69 includes an upstanding coupling piece 74 formed of a straight upper part 75 and a lower part 76 of less width than part 75. The coupling piece 74 is formed in its outer face with a groove 77 which extends from the top to the bottom thereof. The structure 69 includes an

angle-shaped upstanding combined coupling and supporting member 78 formed of an upstanding arm 79 and a horizontally disposed arm 80 which extends inwardly at right angles from the lower end of arm 79. The latter includes a straight upper part and a rearwardly inclined lower part of greater length than said upper part. The latter is arranged in the upper portion of groove 77. The upper portion of said lower part is arranged in the remaining portion of the groove 77. The part 75 of the coupling piece 74 is positioned against and secured to the rear face of flange 70 of bar 68 by the holdfast means 81. The coupling piece 74 depends from flange 70. The upper end of arm 79 is arranged against the rear face of flange 70. The arm 79 is secured to the part 76 of coupling piece 74 by the holdfast means 82 whereby the arm 79 is coupled with or connected to the desk element 22. The arm 79 in close proximity to its lower end has its inner lengthwise edge oppose in close relation the right side edge of seat 46, and said arm is of a length to extend below said seat. The arm 80 of member 78 is disposed below the lower face of seat 46 in proximity to the forward edge 83 of the latter. The arm 80 in vertical cross section consists of an upper horizontal flange 84 and a vertical flange 85 which depends from the front of flange 84. Secured to the lower face of the seat 46 in proximity to its edge 83 is the horizontal flange 86 of an angle bar 87. The latter includes a vertical flange 88 which depends from the front of the flange 86. The right end terminal portion of the angle bar 87 is offset with respect to the remaining portion of such bar to form a space between said offset portion and the lower face of seat 46 whereby a clearance is had for the positioning of arm 80 relative to seat 46. When the arm 80 of member 78 is arranged relatively to the lower face of seat 46, the flange 84 of arm 80 is arranged upon the offset portion of flange 86 of bar 87 and the flange 85 of arm 80 is positioned against the front face of the flange 88 of bar 87. The flanges 84 and 86 are secured together by the holdfast means 89. The parts of the structure 69 and the manner in which they are arranged and secured with the desk element 22 and seat 46 provides for supporting the desk element from and coupling it to the seat 46. The element 22 when coupled and supported is arranged in forwardly extended relation with respect to the chair element 21. The angle bar 87 provides a reinforcement for the seat 46.

A coupling and supporting structure 90 is provided for the rear end of the arm rest element 23 and is disposed at the right side of the back 47 of element 21. The structure 90 includes an angle-shaped member 91 having a horizontal and a vertical flange 92, 93 respectively. The member 91 is disposed diagonally with respect to the rear portion of the lower face of element 23 and has its horizontal flange 92 anchored against said face by the holdfast means 94. The rear end of flange 93 is formed with an angle-shaped extension 95 which overlaps the upper portion and is suitably anchored to the flange 55 of member 48. The structures 69, 90 provide for coupling the one-piece body 61 to and for supporting it from the seat element 21.

The receptacle or book box element 24 is of rectangular contour and open at its top. The element 24 includes an upstanding inner wall 96, an upstanding outer wall 97, a pair of upstanding side walls 98, 99 and a bottom 100. The top and bottom edges of wall 97 are arranged below the

top and bottom edges of wall 96. The top and bottom edges of each side wall incline downwardly from wall 96 to wall 97. The bottom 100 inclines downwardly from the bottom edge of wall 96 to the bottom edge of wall 97. The ends of bottom 100 are spaced equi-distant from the bottoms of the side walls 98, 99. Angle-shaped corner pieces 101 are arranged against the inner faces of said walls, as well as being secured to the latter by holdfast means 102 whereby the walls are coupled together in upstanding relation. Angle-shaped bottom pieces 103 are arranged against the inner faces of the walls 96, 97 and bottom 100 and secured to the latter and the walls 96, 97 whereby the bottom 100 is secured to walls 96, 97 in spaced relation to the walls 98, 99. The manner in which bottom 100 is arranged prevents the accumulation of dirt or dust at the lower portions of the side walls and enables for the expeditious cleaning of element 24 when desired. The form of element 24 provides for increased capacity over a straight bottom box and further facilitates removing a desired book, pamphlet or paper from the box when desired, as the matter stored will be disposed at an inclination. The element 24 is positioned at the right side of seat 46 in outwardly extended lateral relation. The element 24 is arranged below the arm rest element 23, extends above, below and rearwardly from seat 46 and has its forward end oppose the rear face of the arm 79 of member 78. The element 24 is connected to seat 46 by a coupling strip 104 which is secured, as at 106 to the bottom 100 of element 24 and as at 105 to the lower face of seat 46. The element 24 is also coupled to the structure 69 by a hook-shaped member 107 having its shank connected to wall 99 and its bill attached to arm 79 of member 78.

The arm rest 23 has a part of its outer edge 40 73 formed with an inset edge portion whereby in connection with the insert part 72 of the edge 71 the arm rest has its leading portion of greater width than its follower portion. The book box is arranged below the arm rest and has its outer side 45 wall flush with the outer side edge of the leading portion of the arm rest. The narrow follower portion of the arm rests facilitates access to the book box. As the outer side wall of the book box is arranged in the manner as stated aforesaid aisle space is not absorbed.

A modified form of a desk element 108 and an arm rest element 109 are disclosed by Figure 14. The elements 108, 109 are formed from a one-piece body 110 preferably of wood. The difference 50 between element 108 and element 22 is that the former is less in width than the latter and is not provided with the angle bar 65. The difference between the element 109 and element 23 is that the former is not provided with the narrow follower portion as is element 23. Otherwise than that as stated the construction of elements 108, 109 will be the same as that of the elements 22, 23 respectively. The elements 108, 109 will be supported from and coupled to the chair element 65 in the same manner as that of elements 22, 23.

When the unit is anchored to the floor or other support, the foot pieces 39^a may be dispensed with, if desired.

The bottom of base 27 is so formed that upon 70 removal of the foot pieces or shoes the pedestal can be fastened to the floor without alterations by the passage of holdfast means through the apertured corners of the base. When the foot pieces or shoes are removed the pedestal is ready to be attached to the floor. The base of the ped-

estal is so formed that it may be secured to the floor without mechanical changes.

The standard 35 is arranged properly off center with respect to the base 27. The edges 29, 30 and 31 are the bottom edges of the base 27.

The structure 90 is arranged below the upper end of structure 69 to provide for the disposing of the combined desk and arm rest means to extend upwardly at an inclination from rear to front.

Each lower corner of the base 27 of the pedestal may be provided with a separate foot piece or shoe. A form of foot piece or shoe for such purpose is shown by Figures 20 to 23 both inclusive, and generally indicated at 112. One of the lower 15 corners of the base 27 is indicated at 32, Figure 20, and has associated therewith the foot piece 112. The latter consists of a flat strap-like metallic core 113 of angled contour to provide a horizontal leg 114 and a vertical leg 115. The 20 latter extends upwardly at right angles to the inner end and is of materially less length than that of leg 114. The leg 115 in proximity to its upper end has an opening 116. The leg 114 in proximity to its outer end is formed with an opening 117 through which extends a vertical internally threaded bushing 118 projecting above the upper face of leg 114 and formed at its lower end with a lateral flange 119 anchored to the lower face of leg 114. The core 113 is completely 30 encased by a housing 120 formed of cushioning material, preferably rubber. The housing 120 corresponds in contour to the angle shape of the core 113. A part of the material from which housing 120 is formed extends through the opening 116. The housing 120 surrounds the bushing 118 and has its bottom formed with an opening 121 which aligns with the opening or passage formed by the bushing 118. The bottom of housing 120 at its outer end is formed in the same 40 manner as the bottom of housing 44. The foot piece 112 is arranged within the lower portion of the base 27 in the manner shown in Figure 22 with the upstanding part of the foot piece arranged in close proximity to the inner face of the base and the bushing 118 aligning with the opening 122 formed in the corner 32 of base 27. The foot piece 112 is anchored to the base 27 by the holdfast means 123 extending through opening 122 and engaging with the bushing 118. The upstanding part of foot piece 112 prevents the latter from turning relative to base 27.

What I claim is:

1. In an article of furniture, a pedestal element for supporting a chair element including a hollow frusto-pyramidal base and a standard integral at its lower end with the upper end of the base, said base having its sides, front and rear concaved, its side, front and rear lower edges concave and its front and rear lower corners rounded, and oppositely disposed curved flat foot-pieces of strip-like form secured against lower faces at opposed side edges of the base, each of said foot pieces extending from a forward lower corner to a rear lower corner.

2. In an article of furniture, a pedestal element for supporting a chair element including a hollow frusto-pyramidal base and a standard integral at its lower end with the upper end of the base, said base including front and rear lower corners, 70 a pair of flat foot pieces of strip-like form positioned against lower faces at opposite sides of the base, each foot piece extending from a front lower corner to a rear lower corner, and means for securing said foot pieces to said corners.

3. In an article of furniture, a pedestal element for supporting a chair element including a hollow frusto-pyramidal base and a standard integral at its lower end with the upper end of the base, said base being of greater width at its rear than at its front, said base including front and rear lower corners, a pair of flat foot pieces of strip-like form positioned against lower faces at opposite sides of the base, each foot piece extending from a front lower corner to a rear lower corner, means for securing said foot pieces to said corners, said corners being rounded, and said foot pieces being extended outwardly from said corners.

4. In an article of furniture of the type including a pedestal for supporting a chair, said pedestal including a base formed with front and rear lower corners, and a pair of foot pieces, each extending from a front to a rear lower corner and being connected to such corners, said foot pieces being positioned against the lower ends of opposed sides of the base and formed with a cover of soft material to provide friction creating elements relative to the floor upon which the article is positioned.

5. In an article of furniture for the purpose set forth, a chair, a pedestal for supporting the chair formed with a hollow pyramidal base and a pair of oppositely disposed foot pieces of arcuate form positioned against the lower faces of the base at opposed sides of the latter and extending from the forward to the rear lower corners of the base, said base and foot pieces having coacting means for connecting them together.

6. In an article of furniture for the purpose set forth, a seat supporting pedestal including a hollow base having a front wall, a rear wall and

a pair of sides and front and rear lower apertured corners, combined cushioning, protecting and friction creating elements positioned against the lower faces of the edges of the base at the corners of the latter, each of said elements being elongated to extend between certain of said corners and provided with sockets aligning with the apertures in said corners, and means coacting with said sockets for securing the elements to said corners.

7. In an article of furniture for the purpose set forth, a seat supporting pedestal having a hollow base formed of concave sides and rounded front and rear lower corners, a pair of combined cushioning, protecting and friction creating elements of arcuate form positioned against lower faces of opposed sides of said base, each of said elements extending from a front lower corner to a rear lower corner, and means extending through said corners and engaging with said elements for securing them against the bottom face of the base.

8. In an article of furniture for the purpose set forth, a seat supporting pedestal including a hollow base of substantially pyramidal contour having concave sides and rounded apertured front and rear lower corners, a pair of oppositely disposed foot pieces of arcuate contour positioned against the lower faces of opposite sides of said base, each foot piece extending from a front lower corner to a rear lower corner, socket forming means within and at the ends of each foot piece, and means extending through said apertured corners for securing the foot pieces to said base.

WILLIAM J. BARGEN.
